UNITED STATES PATENT OFFICE.

FRANK E. WARNER, OF SEATTLE, WASHINGTON.

FOLDING BOX.

Application filed October 27, 1924. Serial No. 745,959.

This invention relates to folding paper boxes and more particularly to the type employed for containing and displaying merchandise.

5 Its object, generally stated, is the production of a simple and inexpensive box of this character composed of blanks which are folded and arranged so as to enable the box being readily set up to afford a rigid structure, and which may conveniently be collapsed to occupy but little space in storage or transportation.

10 More specific objects and advantages of the invention will appear in the following description.

15 The invention consists in the novel construction, adaptation and combination of parts hereinafter described and claimed.

In the accompanying drawings,—

20 Figure 1 is a perspective view of a box embodying my invention. Fig. 2 is a similar view of the box, parts being broken away, the protective cover being represented in the folded position in which it is used for advertising purposes, the lower or transparent cover being represented in its partly open position. Fig. 3 is a transverse vertical section of the box with the parts arranged substantially as shown in Fig. 2. Fig. 4 is

25 a view of the blank from which the outer sides, ends and protective cover of the box are provided. Fig. 5 is a view of the blank from which the transparent cover, bottom, inner sides and ends of the box are provided. Fig. 6 is a view of the box structure shown collapsed. Fig. 7 is a transverse vertical section to illustrate the box structure during the setting up of the same into a box.

30 According to the present invention I provide a foldable box with an upper and lower cover, in which the latter is provided with a sight aperture for displaying the contents of the box, the upper cover being foldable upon itself and is provided with a tucking flap which is engageable with the wall structure of the box in a manner to retain the upper cover in either a position to permit the lower cover to be opened and closed with respect to the box, or for securing and protecting the lower cover in its closed position.

In carrying out my invention, I cut from card board or the like, two box members or blanks 8 and 9 of substantially the forms represented in Figs. 4 and 5, respectively. The blank 8, shown in Fig. 4, is scored transversely at 10, 11, 12, and 13 so as to be bent

to form a band portion comprising a front fold 14, a back fold 15, side folds 16, 17, and a paste flap 18.

The blank 8, is also scored longitudinally at 19 and 20 for bending to form a cover 21, hereinafter designated as the protective cover, having a tucking flap 22. Said protective cover is, in turn, desirably provided with a crease longitudinally of the blank so as to be foldable upon itself. Said crease may extend from one side of the cover to the other side; but, as represented, the crease is composed of two complementary portions 23 extending from the respective sides to a cut or incision 24 which affords a recess in one of the folds, 25, of the cover and a tongue element 26 coextensive with the other fold 27 of the cover.

The other blank 9 (Fig. 5) is scored transversely at 28, 29 and longitudinally at 30, 31, respectively, so as to enable the blank being bent to form the box bottom 32, a front fold 33, a back fold 34, and side folds 35, 36. The front and side folds of the blank 9 are desirably formed of lengths somewhat greater than the depth of the box, to be scored at 28¹, 29¹ and 31¹ to afford marginal flaps 33¹, 35¹ and 36¹ for the respective folds.

35 Integral with the back fold 34 is an extension which is adapted to be bent at a score 37 to provide a cover 38. This cover, hereinafter defined as the inner cover, is provided with a sight aperture 39 which is closed by means of a transparent sheet 40 which constitutes a part of the cover, said sheet being of celluloid or other suitable material and is indicated in Fig. 5 by dot-and-dash lines.

40 The cover 38 is scored at 41 and 42 to provide side flaps 43 and an end projection, the latter being cut at 44 to provide a thumb piece 45 between two flaps 46.

The flaps 43 and 46 are folded and pasted to the under surface of the transparent sheet 40 for retaining the same in place.

45 After the sheet 40 is thus secured to the paper portion of the cover, the first step in assembling the box parts is to couple the two blanks 8 and 9 together by suitable fastening means such as paste, for example, applied to the stippled areas *a*, *a* (Fig. 4) adjacent the extremities of the front wall 14 of the band portion of the blank 8 to unite the blank 8 against the outer surface of the front fold 33 of blank 9 at the places indi-

cated by *b*, *b* in Fig. 5. After the two blanks have been connected as above explained, the parts are arranged as represented in Fig. 6, that is to say—the side folds 35 and 36 of the blank 9 are laid upon the bottom fold 32 and the back fold 34 and the inner cover are inserted below the side fold 17 and a portion of the back fold 15 of the blank 8, the protective cover 21 occupying its extended position as indicated by dotted lines 21¹ in Fig. 6.

For packing the assembled devices into a smaller space for storage or transportation, the protective cover 21 may be turned back 15 into the position in which it is represented by full lines in Fig. 6.

For setting up the device into box form, the operator first returns the protective cover into its dotted line 21¹ position (Fig. 6) and 20 grasping this cover in his hand he swings the same in such a manner as to carry the band folds 15, 16, and 17 into substantially 25 rectangular relations, one with the other. With the band thus disposed the operator 30 with his other hand pulls the inner cover 38 through the band opening O, see Fig. 7, thereby causing the back fold 34 to be brought into such opening.

Following this, the back fold 34 and side 35 folds 35, 36, of the blank 9 are manually moved against the respective folds of the band portion of the blank 8. When the folds 34, 35 and 36 are so set up they serve with the associated marginal strips 35¹, 36¹ and 33¹ (when turned inwardly as shown in 40 Fig. 2) as locks to prevent the collapsing of the band portion of the blank 8. Such inwardly turned strips also serve to support the cover 38 when the latter is in its closed relation.

To close the box, the thumb piece 45 and the tucking flap 22 of the respective covers are inserted in the interstice between the front folds 14 and 33.

To employ the box for display purposes, the cover 21 as represented in Figs. 2 and 3, is folded upon itself and the tucking flap 22 inserted between the back folds 15 and 34 so as to retain the portion 27 of the protective 50 cover 21 in a position to conspicuously exhibit a sign, or advertising matter which may be employed advantageously upon said cover portion.

Thus arranged, access is readily had to the 55 interior of the box by raising the transparent cover 38 through the instrumentality of the thumb piece 45. This thumb piece is located at the front and the hinge connection of the inner cover at the rear edge of the same, such 60 positioning of the hinge being extremely important and convenient, permitting the box being openable at the front.

While I have illustrated and described the

preferred embodiment of the invention I do not wish to confine myself specifically thereto except as limited by the scope of the appended claims as, for example, instead of uniting the blanks by means of paste, good results are obtainable with the use of staples. Furthermore, changes may be made with respect to the shapes and sizes of the various parts of the two blanks 8 and 9 which constitute the inner and outer members respectively of the box.

What I claim, is,—

1. A folding box comprising an inner member which is scored and folded to provide the box cover, bottom, and inner side, front and back wall elements, said cover being hinged to said back wall, and an outer member which is scored and folded to provide a continuous band to afford outer side, front and back wall elements, and a cover, the last named cover being hinged at its rear edge to the back of said outer member and having at its front a protruding tucking flap, said members being secured together by uniting to afford therebetween an interstice to receive said tucking flap. 75

2. A folding box comprising an inner member having a bottom, front, back and side walls, and a cover hinged to said back wall, and an outer member having front, back and side walls, and a cover hinged to the back wall thereof, said last named cover being foldable upon itself and provided with a tucking flap, said members being connected together to afford between the respective fronts and backs interstices within which said tucking flap is selectively engageable. 90

3. In a folding box, a member folded to provide the box bottom, cover, and rectangular front, rear and side walls, said cover being hinged to the rear wall, said rear wall, being of less height than said front and side walls, the portions of the front and side walls above the plane of the upper edge of the rear wall being turned inwardly of the box to provide a seat for the cover when in its closed position, in combination with a second member having a portion which surrounds the wall structure of the first named member to reinforce the same, said portion having its ends connected together and being secured to one of the walls of the first named member, said second member having another portion provided with a tucking flap, said second named portion being foldable upon itself whereby the tucking flap is adapted to be engaged between the walls of the first named member and the reinforcing portion of the second named member at the front or back of the box selectively. 100

Signed at Seattle Washington, this 6th day of October, 1924.

FRANK E. WARNER.
